United States Patent Office.

THOMAS YOUNG, OF PHILADELPHIA, PENNSYLVANIA.

Design No. 3,748, dated November 9, 1869.

DESIGN FOR THE CONVEX LID OF A DISH OR TUREEN, &c.

The Schedule referred to in these Letters Patent and making part of the same.

I, THOMAS YOUNG, of the city of Philadelphia, in the State of Pennsylvania, have invented and produced a new and original Design for the Raised or Convex Lids or Covers of Tureens, Vegetable and Fruit-Dishes, Chamber-Sets, and other vessels of china, glass, queensware, or crockery, of which the following is a specification.

The nature of my design is fully represented in the accompanying photographic illustration, to which reference is made.

It consists of a depression, *a b c*, made entirely across in the middle of the upper side of a lid, having a raised or elevated middle or centre, so as to afford a clear or unobstructed view of the handle of the said

lid, whether the said handle be made to extend across over from one side to the other of the said depression, as shown in the accompanying photographic illustration, or as a knob in the middle of the depression.

Claim.

I claim, as my invention—

The design for a raised or convex lid or cover, as shown.

THO. YOUNG.
